(57) **CLAIM**

The ornamental design for a shopping cart, as shown and described.

DESCRIPTION

FIG. 1 is a side elevation view of the right and left sides, which are mirror images, of my new design for a shopping cart.

FIG. 2 is a front side elevation view of FIG. 1.

FIG. 3 is a back side elevation view of FIG. 1.

FIG. 4 is a top plan view of FIG. 1.

FIG. 5 is a bottom plan view of FIG. 1.

FIG. 6 is a front perspective view of FIG. 1; and,

FIG. 7 is a front perspective view of the shopping cart, with the top shelf in its alternate position, the only difference being the position of the top shelf, it being understood that all other elements are the same.

1 Claim, 5 Drawing Sheets
